UNITED STATES PATENT OFFICE.

KARL DEINLEIN, OF PILSEN, AUSTRIA-HUNGARY, ASSIGNOR TO THE FIRM OF SKODA WERKE, ACTIENGESELLSCHAFT IN PILSEN, OF PILSEN, AUSTRIA-HUNGARY.

GUN-CARRIAGE.

SPECIFICATION forming part of Letters Patent No. 700,114, dated May 13, 1902.

Application filed December 26, 1901. Serial No. 87,258. (No model.)

To all whom it may concern:

Be it known that I, KARL DEINLEIN, a subject of the Emperor of Austria-Hungary, residing at Pilsen, in the Province of Bohemia, 5 in the Empire of Austria-Hungary, have invented certain new and useful Improvements in Gun-Carriages; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to means for enabling the oscillating spade of a gun-carriage to be rapidly and easily turned from the operative to the inoperative position. For this purpose the bolt connecting the spade to the 20 spring-carrying rod is provided with rectangular projections that fit against arc-shaped guides on the side of the trail and forms when at rest a shaft about which the spade can be turned into the position for transport after 25 its pivot-pin has been withdrawn.

Figure 1 of the accompanying drawings is a sectional side elevation of the rear portion of a gun-carriage according to this invention. Figs. 2 and 3 are respectively a cross-section 30 and a longitudinal section thereof.

A spade S is mounted to oscillate on a detachable pin c, fitting in the two sides of a trail a or in bearings b, mounted thereon, and is connected to a rod d, carrying a coiled 35 spring e, by a bolt f, which is provided at its ends with rectangular projections g, that slide when the spade is oscillated by the recoil of the gun-carriage along two arc-shaped guides h, attached to the sides of the trail. 40 The spade S and the spring-carrying rod d are adapted to rotate on the bolt f. A cross-piece i, which is traversed by the rod d and is rotatably mounted in the sides of the trail, forms the front bearing for the coiled spring e.

45 When the rectangular projections g on the bolt are in their normal positions, they are

located above abutments j—i. e., projecting parts of the sides of the trail—which prevent the spade and the spring-carrying rod from falling when the pin c is withdrawn from its 50 bearings. The spade can then be turned in the direction indicated by the arrow I in Fig. 1 and be fixed in the position indicated by dotted lines by inserting the pin c or any other pin into holes k. The spade might be placed 55 in an inoperative position by rotating it in the direction indicated by the arrow II in Fig. 1 until its lower end bears on the trail-shoe l. The pin c or its equivalent would then of course be inserted into holes in the trail placed 60 in a corresponding position.

I claim—

1. In a gun-carriage, the combination with the trail thereof, of a spade detachably connected thereto, a spring-pressed rod suitably 65 connected with the trail, means for connecting the said rod with the spade, said means provided with projections, guides attached to the trail for the said projections when the spade is oscillated, and means carried by the 70 trail to prevent the dropping down of the spade.

2. In a gun-carriage, the combination with the trail of a spade adapted to operate between the sides of the trail, a pin removably 75 secured to the trail for detachably and pivotally connecting the spade thereto, a spring-pressed rod, a bearing connected with the trail for supporting one end of the rod, a bolt provided with projections, said bolt adapted 80 to connect the other end of the rod to the spade, arched-shaped guides carried by the trail for the said projections when the spade is oscillated, and abutments on the trail to prevent the dropping down of said spade and rod. 85

In testimony that I claim the foregoing as my invention I have signed my name in presence of two subscribing witnesses.

KARL DEINLEIN.

Witnesses:
